UNITED STATES PATENT OFFICE.

CLARENCE O. GRONBERG, OF ELGIN, ILLINOIS, ASSIGNOR OF ONE-THIRD TO ALBERT M. PRICE, OF ELGIN, ILLINOIS.

LEAD PENCIL.

Application filed March 13, 1922. Serial No. 543,381.

My invention relates to lead-pencils of the so-called magazine type in which the leads for use in the pencils are stored; and my primary objects are to provide a novel, simple, durable and inexpensive construction of pencil of the type referred to; to provide a novel, simple and inexpensive construction of magazine; to provide in a pencil of the type referred to mechanism for forcing the leads in succession from the magazine into the outlet portion of the pencil to position the leads for writing; to provide a construction whereby the leads may be readily positioned in the magazine; and, generally, to improve upon pencils of the type above referred to.

Referring to the accompanying drawings:

Figure 1 is a view in elevation, a portion thereof being sectioned, of the body or shell portion of the pencil. Figure 2 is a view in elevation of the other parts of the pencil and with which the body portion of Figure 1 is assembled in use. Figure 3 is a longitudinal sectional view taken through the pencil, with portions thereof broken away; and Figures 4, 5, 6 and 7, sections taken at the lines 4, 5, 6 and 7, respectively, on Fig. 3, and viewed in the directions of the arrows.

The body or shell portion of the pencil, shown as in the form of a hollow cylinder open at its opposite ends, is represented at 8, the magazine for spare leads and the lead-feeding means being located therein. In the particular construction shown the parts of the lead-pencil, other than the shell 8, are provided as a unitary structure, the tip portion of the pencil being shown at 9 and containing a bore 10 extending lengthwise thereof, this bore being shown as disposed eccentrically of the axis of the pencil and in which the lead, represented at 11, is located, when positioned for use, the outer end portion of the tip portion 9 being shown as tapered toward its outer extremity concentric with the bore 10. The tip portion 9 contains a second bore 12 shown as diametrically opposite form to the bore 10 and thru which the leads are inserted into the magazine, hereinafter described, in the charging of the latter with leads. The tip portion 9 is provided with a rod 13 secured at its lower end in the tip portion 9 in any desirable way, as for example by tightly screwing it therein, as shown, the rod 13 being concentric with

the axis of the pencil and projecting at its upper end beyond the portion 9, the upper end of this rod being connected with a circular block 14 containing in its periphery a groove 15 in alignment with the bore 10. 60 The block 14 is rigidly secured to the rod 13 to be non-rotatable thereon, and located between this block and the adjacent end of the tip portion 9 is a cylindrical magazine-forming member 16 which surrounds the rod 13 and is rotatable thereon, the periphery of the member 16 containing parallel grooves extending lengthwise thereof, and represented at 17, for receiving spare leads. An uneven number of the grooves 17 are provided, the member as shown being formed with nine of these grooves, the idea being that when one of the grooves 17 is in line with the bore 10, none of these grooves will be in line with the bore 12, whereby in the position occupied by the magazine when the pencil is in use no opportunity is presented for the sliding of the leads from the grooves 17 thru the bore 12. The block 14 is connected with the lower end of a rod 18, the upper end of which is connected with a collar 19 in which a member 20, at its reduced lower end 21, is journaled. The member 20 has rigidly connected therewith the upper end of a threaded member 20^a, the lower end of which rotatably bears against the upper socketed end of the rod 13, and surrounding the threaded rod 20^a and having threaded engagement therewith at a threaded opening 22 is a member 23 which contains a groove 24 in one edge thereof into which the rod 18 extends, the member 23 being slideable on this rod. The member 23 at the end thereof opposite that containing the groove 24 is connected with the upper end of a lead-feeding rod 25 which is arranged in line with the slot 15 in the block 14 and in which it is lengthwise movable, to force the lead located in the particular one of the grooves 17 in alignment with the groove 15, thru the bore 10 and into a position in which it may be used for writing. The rod 25 is operated, for the purpose stated, by the operator rotating the member 20 in clockwise direction in Fig. 4, the rotation of the threaded rod 20^a in engagement with the threaded opening in the member 23, and the latter, being held against rotation, serving to force the member 23 toward the block 14. 100

The block 14 contains in its periphery a 110

longitudinal groove 26 in which a pawl 27 is located and lengthwise movable, this groove being of dove-tail form in cross-section and the pawl being of similar cross-section to prevent accidental displacement of the latter. The pawl 27 which is shown as formed at one side with an abrupt shoulder surface, is normally yieldingly pressed toward the tip of the pencil, as by a spring 10 represented at 28, one end of this spring being rigidly connected at 28^a with the block 14 and at its opposite end, represented at 30, yieldingly pressing against the upper end of the pawl 27.

15 In assembling the structure shown in Fig. 2, within the shell 8, it is introduced at its portion 20, the cap 29 being removed, into one end of the shell and moved lengthwise therein to a position in which the section 9 20 at its end abuts the shell, as shown in Fig. 3, in which position the part 20 extends beyond the opposite end of the shell and has preferably applied thereto the cap 29 which fits the member 20 sufficiently tightly to permit the latter to be turned thru the medium of this cap 29.

The structure located within the shell, preferably at some portion thereof which will not interfere with the sliding of the member 23 into the shell 8, fits the shell sufficiently tightly to hold the rod 18 against movement in the rotation of the member 20, in order that the lead may be fed thru the bore 10 as desired. The relatively tight fit referred to is preferably between the rotatable magazine member 16 and the inner surface of the shell 8.

It will be noted that the pawl 27 is so positioned that when the lead-feeding rod 25 is 40 in line with one of the lead-receiving grooves 17, this pawl will extend into one of the other of these grooves 17.

The grooves 17 of the magazine are charged with leads, preferably through the bore 12, and to accomplish this the operator rotates the member 20 to a position in which the rod 25 is retracted from the magazine 16, thereby permitting the magazine member 16 to be freely rotated in clockwise direction in Fig. 6 relative to the rod 25 by turning the shell 8 or rotating the member in anti-clockwise direction, relative to the shell 8 while holding the latter against rotation for 45 moving the ends of the grooves 17 into registration successively with the bore 12.

The magazine being charged, the operator then rotates the member 20 in clockwise direction in Fig. 4 which causes the rod 25 60 to feed the lead 11 through the bore 10 by engaging with the upper end of the lead. When it is desired to move one of the spare leads in the magazine into a position in which it may be forced through the bore 10 65 for writing, the operator rotates the member

20 in anti-clockwise direction in Fig. 4 to a position in which the rod 25 is entirely withdrawn from the groove 17 in which it was operating in which position the nut member 23 engages the underside of the reduced portion 21 of the member 20, the operator continuing to rotate the member 20 with one hand while grasping the shell 8 with his other hand with the result of rotating all the parts shown in Fig. 2 except the magazine member 16 which is held against rotation by frictional engagement with the inner surface of the shell 8 as hereinbefore described. Thus, the rotation of the member 20 throughout substantially one-ninth of a complete revolution in the particular construction illustrated, shifts the rod 25 bodily about the axis of the pencil to a position in which it aligns with the groove 17 next to the one in which it operated in the lead-feeding operation as above stated, the pawl 27 in the movement of the parts as stated riding over the end of the rib between these two grooves and springing into the next one beyond, which not only apprises the operator that the next spare lead is in position to be operated on by the feed-rod 25, but also positively prevents the rotation of the block 14 relative to the magazine member 16 in the initial stages of the lead-feeding operation, it being noted that the pawl 27 as shown is so constructed that it forms an abutment co-operating with the wall of the groove into which it extends, to prevent the block 14 from rotating in clockwise direction in Fig. 5. It will be noted that inasmuch as the rod 25 enters the grooves 17 in the magazine the latter is prevented from rotating in either direction and thus danger 105 of accidental turning of the tip portion 9 and the magazine relative to each other and the breaking of the lead thereby is avoided.

It will be noted that in the particular construction shown, the shell 8 forms the main body of the pencil, and the parts forming the interior mechanism may be assembled therewith, and disassembled therefrom, without disconnecting such parts these parts in effect being formed as a unitary structure 110 insertable and withdrawable from the shell. This is not only of advantage in connection with the manufacture of the pencil, permitting the parts to be quickly and easily assembled, but is also of advantage in that it 115 permits of ready access to the interior of the pencil for inspection or repair, and the ready reassembly of the shell member with the unitary interior mechanism.

Furthermore, the shell 8 serves as a cover 125 for the open-sided lead-receiving grooves of the magazine 16, and as the shell 8 and magazine 16 are relatively movable lengthwise of the pencil, the operator merely by shifting these parts relative to each other 130

lengthwise of the pencil may have ready access to the magazine, as for example to inspect the leads to determine which, if any, of the grooves in the magazine still contain 5 leads and to aid in quickly positioning those grooves in which leads remain, in alignment with the passage in the tip, the feature just referred to also permitting of the ready removal of broken or defective leads from the 10 magazine, as well as aiding in the placing of leads in the magazine.

While I have illustrated and described a particular construction embodying my invention, I do not wish to be understood as 15 intending to limit it thereto, as the same may be variously modified and altered without departing from the spirit of my invention.

What I claim as new, and desire to secure 20 by Letters Patent, is:

1. A lead-pencil comprising lead-forcing means having a rod portion extending lengthwise of the axis of the pencil and eccentrically thereto, means whereby the leads 25 are disposed in a circular series in the pencil, said lead-forcing means being adapted at said rod portion to successively engage the leads and feed them into position for use, and means whereby alignment of said leads 30 in succession with said lead-forcing means may be effected, said rod portion of said lead-forcing means in its movement in feeding a lead moving to a position beyond said last-named means.

35 2. A lead pencil comprising a lead-magazine and lead-forcing means for successively engaging the leads in the magazine and feeding them therethrough into position for use comprising a lead-engaging element and rotary means for actuating said element operating, when rotated in one direction, to actuate said element to feed a lead and when 40 reversely rotated to retract said element from the magazine and operating, when rotation thereof is continued after moving said element to retracted position, to effect relative 45 bodily rotation of said lead-forcing means and said magazine.

50 3. A lead pencil comprising a member containing a passage in which the lead when in position for use extends, a second member (lead-magazine) containing a series of passages extending lengthwise thereof, and lead-forcing means for successively engaging the 55 leads in the magazine and feeding them therethrough and into the passage in said first-named member, said means comprising a lead-engaging element and rotary means for actuating said element operating, when 60 rotated in one direction, to actuate said element to feed the lead and when reversely rotated to retract said element from the magazine and operating, when rotation thereof is continued after moving said element to retracted position, to effect relative 65

bodily rotation of said first-named means and said first-named member jointly and said second member.

4. A lead pencil comprising a member containing a passage in which the lead when 70 in position for use extends, a second member (lead-magazine) containing a series of passages extending lengthwise thereof, and lead-forcing means for successively engaging the leads in the magazine and feeding them 75 therethrough and into the passage in said first-named member, said means operating when rotated in one direction to feed the lead and when reversely rotated to retract said element and operating, when rotation 80 thereof is continued after moving said element to retracted position, to effect relative bodily rotation of said first-named member and said first-named means jointly and said second member, and means preventing relative 85 rotation of said first-named member and said first-named means jointly and said second member during the operation of said rotary means for feeding a lead.

5. A lead pencil comprising a shell 90 composing the body of the pencil, a lead-magazine extending into said shell, and lead-forcing means for successively engaging the leads in the magazine and feeding them 95 therethrough into position for use, said magazine being held in said shell against rotation therein and said lead-feeding means being rotatable relative to said magazine for aligning the leads in the latter in succession with said lead-forcing means.

100 6. A lead pencil comprising a shell and tip portion at one end of said shell, a lead-magazine extending into said shell and said tip portion being rotatable relative to said shell and to said magazine and said magazine being held in said shell against rotation, and lead-forcing means extending into the other end of said shell for successively 105 engaging the leads in the magazine and feeding them therethrough and through said tip portion, said lead-forcing means being connected with said tip portion to prevent relative 110 bodily rotation thereof.

115 7. A lead pencil comprising a shell composing the body of the pencil, a lead-magazine extending into said shell and held therein against rotation, and lead-forcing means extending into said shell for successively engaging the leads in the magazine and feeding them therethrough into position for use, 120 said shell and said means being bodily relatively rotatable when said means are in retracted position.

125 8. A lead pencil comprising a shell, a lead-magazine extending into said shell and held therein against rotation, and lead-forcing means extending into said shell for successively engaging the leads in the magazine and feeding them therethrough into position for use, said lead-forcing means com- 130

prising a lead-engaging element and rotary means for actuating said element operating, when rotated in one direction, to actuate said element to feed the lead and when reversely rotated to retract said element from said magazine and operating, when rotation thereof is continued after moving said element to retracted position, to effect relative bodily rotation of said lead-forcing means and said shell.

9. A lead pencil comprising a shell, a lead-magazine extending into said shell and held therein against rotation, and lead-forcing means extending into said shell for successively engaging the leads in the magazine and feeding them therethrough into position for use, said shell and said means being bodily relatively rotatable when said means are in retracted position, and means preventing relative rotation of said magazine and said first-named means in one direction.

10. A lead pencil comprising a shell, a tip portion located at one end of the shell and containing a passage for receiving a lead, a rod connected with said tip portion, a lead-magazine having journal support on said rod and containing a series of passages extending lengthwise thereof and grouped about its center and so positioned that they may be successively moved into alinement with the passage in said tip portion upon relatively rotating these parts, said magazine extending into said shell and being held against rotation relative to the latter, a screw-threaded member rotatable in said shell, a block movable lengthwise of the shell and having threaded engagement with said threaded rod, a rod extending lengthwise of the pencil and held in alinement with the passage in said tip portion, said last-named rod being operated by the movement of said block lengthwise of the pencil, means preventing rotation of said block relative to said tip portion, and means cooperating with said block and operating when the latter is moved to a position in which said last-named rod is retracted from said magazine, to effect bodily rotation of said last-named rod about the axis of the pencil, and relative to said shell and magazine, in the rotation of said threaded rod in the direction for retracting the lead-engaging rod, whereby the latter is moved into line with the passages in said magazine, in succession.

11. A lead pencil comprising a shell, a tip portion located at one end of the shell and containing a passage for receiving a lead, a rod connected with said tip portion, a lead-magazine having journal support on said rod and containing a series of passages extending lengthwise thereof and grouped about its center and so positioned that they may be successively moved into alinement with the passage in said tip portion upon

relatively rotating these parts, said magazine extending into said shell and being held against rotation relative to the latter, a screw-threaded member rotatable in said shell, a block movable lengthwise of the shell and having threaded engagement with said threaded rod, a rod extending lengthwise of the pencil and held in alinement with the passage in said tip portion, said last-named rod being operated by the movement of said block lengthwise of the pencil, means preventing rotation of said block relative to said tip portion, and means cooperating with said block and operating when the latter is moved to a position in which said last-named rod is retracted from said magazine, to effect bodily rotation of said last-named rod about the axis of the pencil and relative to said shell and magazine, in the rotation of said threaded rod in the direction for retracting the lead-engaging rod, whereby the latter is moved into line with the passages in said magazine, in succession, and means preventing relative rotation of said magazine and said lead-engaging rod about the axis of the pencil, in one direction.

12. A lead pencil comprising a shell open at its opposite ends, a tip portion at one end of the shell and containing a passage for a lead extending eccentrically of the axis of the pencil, a rod connected at one end with said tip portion and located in said shell with its opposite end of enlarged diameter forming a head, a magazine rotatably mounted on said rod between said tip portion and said head and containing a series of passages extending lengthwise thereof for receiving leads and adapted to be moved in succession into alinement with the passage in said tip portion, said head containing a passageway in its periphery for alinement with the passages in said magazine, in succession, a bearing member at the other end of said shell, a rod connecting said bearing member with said head, a threaded rod journaled in said bearing member, a nut with which said threaded rod has threaded engagement, said nut engaging said last-named rod for preventing rotation of said nut, a lead-engaging rod operatively engaging said nut and adapted to move lengthwise in said magazine, said magazine being held against rotation within said shell, and a pawl carried by said head and adapted to cooperate with the notches in said magazine.

13. A lead pencil comprising a tip portion containing a passage therethrough for the lead when positioned for use, and a second passage forming an inlet for leads, and a lead-magazine containing a series of lengthwise-extending passages adapted to be moved in succession into registration with said second passage in said tip portion to permit of the charging of the magazine with

leads, the passages in said magazine and the passages in said tip portion being so arranged that when a passage in the magazine registers with the first-referred-to 5 passage in said tip portion, said second passage in said tip portion is not in registration with any of the passages in said magazine.

14. A lead pencil comprising a tip portion 10 containing a passage therethrough for the lead when positioned for use, and a second passage forming an inlet for leads, and a lead-magazine containing a series of lengthwise-extending passages adapted to be 15 moved in succession into registration with said second passage in said tip portion to permit of the charging of the magazine with leads, the passages in said magazine and the passages in said tip portion being so arranged that when a passage in the magazine 20 registers with the first-referred-to passage in said tip portion, said second passage in said tip portion is not in registration with any of the passages in said magazine, and 25 lead-forcing means involving a member which operates in the one of said passages in said magazine in alinement with said first-named passage in said tip portion.

15. A lead pencil comprising a tip portion 30 containing a passage therethrough for a lead when positioned for use, and a second passage forming an inlet for leads, said passages being diametrically opposed, and a lead-magazine containing a series of 35 passages of an odd number adapted to be moved in succession into registration with said second passage in said tip portion to permit of the charging of the magazine.

16. A lead pencil comprising a tip portion 40 containing a passage therethrough for a lead when positioned for use, and a second passage forming an inlet for leads, said passages being diametrically opposed, a lead-magazine containing a series of passages of 45 an odd number adapted to be moved in succession into registration with said second passage in said tip portion to permit of the charging of the magazine, and lead-forcing means involving a member which operates in 50 the one of said passages in said magazine in alinement with said first-named passage in said tip portion.

17. A lead pencil comprising a shell, a lead-magazine extending into said shell and held therein against rotation, and lead-forcing means extending into said shell for successively engaging the leads in the magazine and feeding them therethrough into position for use, said shell and said means being 55 bodily rotatable relative to each other for alining the leads in succession in the magazine with said lead-forcing means, said means extending into said magazine in one position of said means and holding said 60 magazine and means against relative rotation.

tion bodily and being retractable to permit said magazine and means to be relatively rotatable bodily.

18. In a lead pencil, the combination of a tip containing a passage for a lead when positioned for use, a lead-magazine, said tip and magazine being relatively movable, and lead-forcing means for forcing a lead from the magazine into said passage, all of said parts being connected together to form a unit, and a shell into which said unit is insertable for assembling the parts of the pencil without disassembling the parts comprising said unit.

19. In a lead pencil, the combination of a tip containing a passage for a lead when positioned for use, a lead-magazine, said tip and magazine being relatively rotatable, and lead-forcing means for forcing a lead from the magazine into said passage, all of said parts being connected together to form a unit, and a shell into which said unit is insertable for assembling the parts of the pencil without disassembling the parts comprising said unit.

20. In a lead pencil, the combination of a tip containing a passage for a lead when positioned for use, a lead-magazine containing a series of open-sided grooves for leads, said tip and magazine being relatively movable and lead-forcing means for forcing a lead from the magazine into said passage, all of said parts being connected together to form a unit, and a shell into which said unit is insertable for assembling the parts of a pencil, without disassembling the parts comprising said unit.

21. In a lead pencil, the combination of a member containing a passage for a lead when positioned for use, a lead-magazine containing open-sided grooves for leads, said member and said magazine being relatively movable to successively position said grooves in line with said passage, and a shell forming a cover for the leads in the grooves, said magazine and shell being relatively movable lengthwise of the pencil.

22. A magazine pencil, comprising a main body, means for gripping a lead or crayon in projected operative position, means for coupling said gripping means to said main body in longitudinally spaced relation below the latter, a rotary magazine journaled on said coupling means intermediate said main body and gripping means, said magazine having a plurality of chambers for holding leads or crayons adapted to be selectively disposed in operative relation to said gripping means by rotating said magazine, and a longitudinally movable feed rod connected with said main body and movable through an operatively disposed magazine chamber to engage and feed a lead or crayon out of the same into operative relation to said gripping means.

23. A lead pencil comprising a lead magazine into which the leads are arranged about the axis of the pencil, and lead feeding means comprising a feed-rod eccentric to the axis of the pencil and slideable into and out of said magazine, a rotatable feed-rod-operating member concentric with the axis of the pencil

and means operated by rotation of said member for actuating said feed rod, said magazine and said lead feeding means being relatively rotatable to successively align the leads in said magazine with said feed rod. 10

CLARENCE O. GRONBERG.
